UNITED STATES PATENT OFFICE

WILLIAM A. ZEIDLER, OF NEW YORK, N. Y., ASSIGNOR TO THE ZEIDLER CORPORATION,
OF NEW YORK, N. Y., A CORPORATION OF NEW YORK

GARMENT PRESS

Application filed January 27, 1925, Serial No. 5,118. Renewed July 2, 1929.

This invention pertains to garment presses and to that general type wherein two relatively movable pressing elements are employed, one a so-called fixed buck and the other a head movable toward and from the buck. 50

Presses of this type, as now usually constructed, are open to several objections, a serious one being a drag of the head across the 10 garment as the press is being brought to its closed position, which drag tends to displace the lay of the garment on the buck. A further objection resides in the fact that the head does not move away from the buck to any considerable extent when the press is open with the 15 consequence that the operator has difficulty in properly positioning the garment, particularly at the rear portion of the buck. This closeness of position also necessitates the operator bringing his (or her) face into close proximity to the heated head and buck in an effort to obtain a view of the garment when it is being positioned and smoothed out by hand. 20

Again, most garment presses as commercially employed today, involve the use of a lever for carrying the head, the lever being pivoted to the rear portion of the frame. As a consequence the head swings in the arc of a 25 circle and the movement necessitates the operator reaching up to a considerable height and exerting considerable energy in the act of drawing the head forwardly and downwardly. The present invention seeks to overcome these and other objections and to provide among other things a press wherein the head moves away from the buck to such an extent as to leave the buck entirely clear for the placement of the garment. The arrangement 30 is such that the head moves in a right line or perpendicular to the buck, when pressure is being exerted and relieved, and, in its forward and rearward movements stands above and entirely out of contact with the work on the 35 buck, hence there is no drag on the work at any time. The design of the press is such that the same may be operated with a minimum of effort owing to the fact that the head is mounted on a rocking support. Furthermore, the pedal utilized to effect the pressure between the pressing elements swings through a short distance only and in an approximately horizontal plane, a point of manifest advantage over the usual lever mechanism which has quite an amplitude of vertical movement. 55

Where the press is used for laundry work, this ease of treadle movement is highly important as a woman may easily actuate the pedal and in fact may be seated during the use of the press. The manner of supporting the head is such that it may be said to have a universal movement when applying pressure, and by reason of this it will accommodate itself to different thicknesses of goods which may be placed on the buck, —thus relieving the parts from strain and effecting substantially even pressure throughout. 60

With these advantages in view, and others as will appear in the following description, reference is had to the annexed drawings disclosing the preferred embodiment of the 65 press, wherein:

Fig. 1 is an end elevation of the press in its fully opened position; 70

Fig. 2 a vertical sectional view showing the head brought forward preparatory to being drawn down upon the buck, the table of the press being partly broken away; 75

Fig. 3 a like view showing the press closed; 80

Fig. 4 a front view, partly in section, with the press in closed position, the table being omitted; 85

Fig. 5 a horizontal sectional view showing the relation of the treadle and locking mechanism when the press is open;

Fig. 6 a similar view of the same parts with the press closed; 90

Fig. 7 a detail sectional elevation of a

portion of the buck and head and allied steam pipes;

5 Fig. 8 a perspective view of a portion of the buck and the piping used to heat the buck, to eject steam through the foraminous face thereof and to produce a suction downwardly therethrough;

Fig. 9 a detail elevation;

10 Fig. 10 a plan view of the adjustable support upon which the thrust or pressure exerting frame is fulcrumed;

Fig. 11 a detail view of the head steaming valve connection; and

15 Fig. 12 a perspective view of a portion of the tilting rocker supporting frame and a portion of the rocker frame.

20 In the drawings 1 denotes the bed or base of the machine shown as having a U-shaped outline (Figs. 5 and 6) arising from the forward part of which is a fixed supporting frame comprising two side frames 2 and 3 connected or merging into each other at their upper ends by a horizontal cross bed or head 4. As will be noted, these elements are 25 shown as angular in cross-section to afford strength and rigidity along with lightness.

Extending upwardly from the head is a supporting column 5 to which in turn is secured the buck or lower pressing element 6, 30 of any desired contour.

35 Pivotedly secured upon a cross rod 7 secured in lugs 8 at the rear of the base 1, is a tilting platform comprising two side bars or rails 9 and 10 and connecting cross bars 11, 12 and 13.

40 Bars or rails 9 and 10 are alike in form and extend forwardly between the side frames 2 and 3 to the forward portion of the base. Forward of the cross bar 12 each rail or bar, 9-10, is provided on its upper face with a camming face 14 which at its extreme forward end terminates in a seat or depression 15 having an upturned outer end 16, the purpose of which will presently appear.

45 Extending outwardly from each of the members 9 and 10 is a lug 17 and springs 18 extend upwardly therefrom to cross pins 19, Figs. 1 and 4, seated in recesses formed in the frame member 4. The springs are placed under stress when positioned and serve to swing or draw the platform upwardly and to elevate the head and its supporting rockers which latter are mounted for rolling motion 55 on the bars 9 and 10 which are in effect, to the rear of the lugs 17, tracks upon which the rockers roll.

50 The head or upper pressing element is designated by 20. Extending upwardly therefrom are two pairs of spaced lugs 21 and 22, and 21a and 22a, Figs. 4 and 7, between which are pivotally secured the upper ends of the respective supporting arms or frame members 23 and 24. Coiled springs 25 and 65 26 are interposed between said members and

the head, so that the head may be rocked or turned slightly. Members 23 and 24, as will be seen, curve inwardly over the head while at the lower ends they are each provided with an arcuate or rocker like members 27 and 28 70 respectively, shown as formed integral with their respective head supporting members and standing to the rear thereof. Said rockers are each provided with a downwardly extending flange along their outer side as indicated at 29 which flanges pass downwardly beside the members 9 and 10 and serve to prevent lateral displacement of the rockers.

75 Members 23 and 24 are tied together by suitable cross-bracing, as braces 30 and 31 80 while the rockers are tied together by cross-frame 31a best seen in Figs. 5 and 6. The members 23 and 24, together with the rockers or arcuate shaped members 27 and 28 and the various braces, form in effect a rocking or 85 rolling support frame for the head and by reason of the manner in which they are proportioned and formed, the parts are practically counterbalanced and the rockers may be rolled over the track portions of the pivot- 90 ed platform with practically no effort.

95 Stated in another way, the arcuate elements, and the head 20 supported thereby, roll on the tracks without substantial vertical movement of their combined center of gravity. Preferably the parts are so proportioned that the head will normally swing to the rear or to the full open position of the press. On the other hand by merely pressing down upon a pedal 50, hereinafter more fully described, 100 the head carrying frame will rock forwardly and bring the head over the buck. To limit this swinging movement of the rocking frame in each direction, the frame is provided at its lower forward portion on each side with a laterally extending pin 32, which pins extend freely into the slightly curved slots 33 formed in upstanding arms or lugs 34 projecting upwardly from the side members 9 and 10 of the pivoted platform or rocker support.

105 To relieve the parts from any jar and to prevent the noise of impact of the press as the head reaches its limit of rearward movement, there is provided an air check comprising a cylinder 35, a plunger 36, a chain 37 connected thereto, and a bail shaped member 38 attached to the chain and pivotally connected at its opposite end to the upper portion of a cross bar 39 extending between the cross braces 30 and 31, see Fig. 9. Outward movement of the plunger is checked by entrapped air within the cylinder, and just prior to the head reaching the limit of its rearward movement, the chain and bail are 110 brought into alinement and pull is exerted on the plunger. The latter checks the movement of the head and prevents hammering of the parts. When the head is drawn over the buck, cross bar 39 contacts the plunger 115 120 125 130

and moves it inwardly—see Fig. 2—so that it may act again to check the parts when drawn outwardly.

To lock the rocker frame to the pivoted platform upon which it is supported, when the head is drawn forwardly over the buck, and to depress said platform and consequently the rolling or rocker frame to bring the head downwardly into pressing relation to the buck, the following mechanism is employed.

Extending downwardly from the under face of frame element 4, see Figs. 2 and 10, is a pair of lugs 40, 41, through which extends a bar or rod 42 forming the pivot for a bail shaped frame 43. In the forward part of the frame there is mounted for rotation a rod 44, the lower end whereof is fashioned into a handle while the upper end is threaded and takes into a threaded opening formed in the frame element 4, see Figs. 3 and 4. Frame 43 is so formed that the handle of the rod extends below the skirt of element 4 so that the operator may have ready access thereto for the purpose of raising or lowering the frame.

The frame forms an adjustable fulcrum support for what may be termed a thrust frame which, when it is swung inwardly forces the swinging platform downwardly and thereby draws the head 20 down on the buck into pressing relation thereto. The thrust frame in the form shown comprises two vertically disposed side bars 45 and 46 cross-connected by braces 47 and 48, the bars at their upper ends being pivotally connected to the frame 43, as by a rod 49. By turning the rod 44, frame 43 may be raised or lowered, thereby varying the effective length of the thrust frame and consequently producing different degrees of pressure between the head and buck as may be desired and necessary.

Adjacent the lower ends of the bars 45 and 46, and between the same, there is secured a pedal 50, the pedal being quite wide and extending outwardly in such position that the press operator may readily place his foot thereon. The lower end of each of the thrust frame members 45 and 46 is bifurcated and a roller as 51 and 52 is respectively mounted in said bifurcated ends. Said rollers bear directly upon the forward portions of the arms 9 and 10 of the swinging or tilting platform and when the press is open, with the head thrown to the rear—see Fig. 1—said rollers rest within the pockets or depressions 15 and are held from rolling forwardly out of the same by the upstanding projection 16 of the pocket. As the thrust frame is swung inwardly at its lower end, which is accomplished by merely pressing the treadle inwardly, the rollers ride up and along the cam faces 14 of the arms 9 and 10, and as a consequence force the platform to swing downwardly, drawing the rocker frame with it and

consequently drawing the head 20 down into pressing contact with the buck. This assumes that the rocker frame is locked to the tilting rocker supporting platform and to effect such interconnection the following mechanism is employed.

Pedal 50 at its inner edge is formed with an inward extension 50a having two lugs or fingers 53 and 54 extending inwardly therefrom, in which is secured a pin 55. Swivelled upon the pin, between the lugs is block or casting 56 to which is secured the rear ends of a camming member formed from a bar bent to the desired form. This member may be said to comprise two outer parallel sections 57 and 57a connected by an end loop 58, two divergent camming sections 59 and 59a and two other parallel sections 60 and 60a, the ends whereof are removably secured in the block 56. This camming element, or more specifically, the side bars thereof, each pass through an opening formed in the inner end of a pair of sliding bolts 61 and 62 which are mounted for endwise movement in suitable lugs, as 63, extending upwardly from the cross bar or brace 12. These bolts are designed when projected outwardly to pass into openings 64, which are somewhat elongated, formed in the lower forward portions of the rocker frame, or more specifically in the members 23 and 24 thereof, when said frame is rocked forwardly into the position shown in Fig. 2. The frame may be readily drawn forward to this position from that in Fig. 1 by a slight pull exerted by the operator upon a handle bar 65 mounted for rotation in arms 66 and 67 secured to and extending outwardly from the head 20, Fig. 4. So too the head may be brought forwardly into vertical alignment with the buck by a slight pressure upon the pedal 50. In other words the parts are so counterbalanced that little or no effort is required to swing the frame forwardly.

In use of the press, as the operator about completes the forward pull just mentioned, the pedal is thrust inwardly and as a consequence the bolts are moved outwardly locking the rocking or rolling carriage to the tiltable platform upon which it is supported. Such inward movement of the treadle also carries the thrust frame or element inwardly toward a vertical position, Fig. 3, the rollers passing up the cam faces 14 and onto the adjacent portions of the arms 9 and 10 at which time the head will move downwardly in a right line into pressing contact with the goods imposed upon the buck. An outward movement of the treadle, which takes place automatically through the action of the springs 18 serving to lift the platform which latter causes the thrust member to swing outwardly at the lower end, carries the camming member with it which acts to retract the bolts and to hold them in their retracted position.

- There is an ease of closing and opening of the press which is due to the angular relation which obtains between the thrust frame and the pivoted platform which approximates but never reaches a right angle under any condition. If thrown inwardly to or beyond a right angle, the thrust member would not be automatically moved outward by action of the springs 18 upon release of the pedal.
- 10 A check cylinder 68, see Figs. 5 and 6, is secured to the cross-brace 11 of the swinging platform, the piston whereof is forced rearwardly by a spring, while the piston rod 69 is connected by a chain 70 to the loop end 58 of the camming or bolt actuating member. This arrangement serves to check the outward movement of the thrust frame and treadle at such time as the rollers pass into the pockets or recesses 15 where the rollers come to rest.
- 15 To hold the press in its closed position, a pivoted latch is provided. It may be said to comprise an open frame-like member 71 pivoted upon the ends of rod 55, the outer portion of the frame underlying the pedal extension 50a and provided with an upstanding knob or button 72 which passes upwardly through an opening formed in the extension.
- 20 At its inner end the frame is provided with two arms 73 and 74 each having a finger 75 adapted to engage shoulders 76—see Figs. 3 and 12 formed upon the upper portion of the innermost pair of lugs 63. When the pedal is pushed to its innermost position with the press in its closed position, the fingers engage the shoulders and hold the parts against retrograde movement. A tension spring 77 interposed between the latch frame and the under face of the treadle serves to rock the latch so that the fingers will automatically engage the locking shoulders. A slight touch of the operator's foot upon knob or button 72 releases the latch and allows the press to automatically open.
- 25 The elongation of the openings 64 permits of a slight sidewise movement of the rocking frame with reference to the locking bolts, which motion is of course multiplied many times at the upper end thereof. As a consequence, the frame may be tilted upon one or the other rocker even when the frame is locked to the platform and it naturally follows that the head is also tilted endwise. This freedom of movement coupled up with the freedom of the head to rock transversely owing to the pivoting thereof, allows the head to accommodate itself to goods of uneven thickness which may be imposed upon the buck,—a point of manifest advantage. In fact, the head may be said to have a universal movement which however in nowise affects the application of pressure thereto.
- 30 Where the press is utilized as a garment press, as contra-distinguished from a laundry press, while the pressing elements may vary in contour, the actuating mechanism therefor remains the same. It is desirable when pressing garments to eject steam thereon to soften the same and to raise the nap prior to the final pressing operation. Such steam treatment is not, however, essential to laundry pressing. Vacuum producing means is also desirable under both operations. There is therefore illustrated in the drawings standard means or piping, together with valve controls, for heating the head and buck, for producing steam ejection through the head and also through the buck, and also for producing the suction or "vacuum" through the buck. The connections in the present case between the supply pipe and the head differ from the usual practice in that there are provided universal joints which allow the head to tilt in all directions as above specified without placing any strain on the pipes or connections, or upon the head.
- 35 Thus referring to the drawings and more particularly to Figs. 7 and 8, 78 denotes the steam supply pipe leading from any suitable source, the pipe being secured to the rear of the frame by a bracket-T-fitting as 79. A nipple 80 is threaded into the fitting and screwed thereon is one member of a ball jointed coupling 81. A pipe 82 is connected into the other member of said coupling, the pipe in turn at its upper end being connected to a second pipe 83 through a similar coupling 84. Pipe 83 is connected to one end of the upper live steam chamber 84b of the head 20 through a third ball coupling 85.
- 40 Chamber 84b at its opposite end is connected into the steam exhaust or return line 86 by similar pipe sections and couplings, the parts being similarly numbered with the exponent *a* added thereto.
- 45 By the arrangement just described, an effective, yet flexible, piping is provided for the head and one which imposes no drag on the head in the opening and closing movements thereof.
- 50 Furthermore, the construction permits the universal movement of the head above described.
- 55 A head valve 87 to admit steam from the chamber 84 is provided, the operating lever whereof is connected to handle 65 through a link 88 and arm 89 connected to the handle. Line 78 is connected by a branch 90 to the heating chamber 91 of the buck into which latter is connected a return line 92, said pipes or branches extending up through the hollow support 5 and thus being out of the way.
- 60 A pipe 93 extends through chamber 91 and opens into the space beneath the perforate covering plate which overlies the buck, the pipe being connected into the steam lines as usual to permit steam to pass upwardly therethrough or to have a suction produced therein to effect the usual "vacuum." As the valves for controlling these actions are well

known, they are not described herein, though illustrated in the drawings. The usual table and buck board are omitted from the drawings for the sake of clearness; they are, however, partially indicated in dotted lines in Fig. 2.

It is of course conceivable that the means for locking the rocking support to the tiltable platform and the means for actuating the thrust member could be made independent, but the arrangement illustrated is preferred as but a single pedal with but a single movement is necessary, which leads to simplicity of manipulation.

This application is a continuation in part of my prior application, Serial No. 699,335, filed March 14th, 1924.

What is claimed is:

1. In a garment press, the combination of a fixed frame; a buck mounted thereon; a pivoted platform having tracks and cam surfaces formed as extensions of the forward portion of said tracks; a rocking supporting frame mounted upon said tracks; a head carried by the upper portion of said rocking frame; means for normally raising the free end of the platform and thereby holding the head in a plane above the buck; a thrust member pivotally mounted at its upper end; rollers carried at the lower end of said thrust member and contacting the cam surfaces aforesaid; a pedal secured to the thrust member; bolts mounted upon the supporting platform and adapted to enter openings formed in the rocking frame when the latter is drawn forwardly to bring the head over the buck, and means associated with the thrust frame for projecting and retracting said bolts.

2. In a garment press, the combination of a fixed frame; a buck mounted thereon; a platform pivotally supported at its rear end, said platform having tracks formed thereon with cam faces at the forward portions thereof; a rocking supporting frame mounted for rolling movement upon the tracks; a head carried by the upper portion of said frame; means acting constantly to raise the forward end of the supporting platform; a thrust member pivotally supported at its upper end; rollers carried by the lower portion of said thrust member and normally contacting the cam faces aforesaid; a treadle secured to the thrust member; a pair of reciprocating bolts mounted upon the supporting platform, means pivotally associated with the thrust member and treadle acting upon the bolts to force the same outwardly upon an inward movement of the treadle and thrust member, said bolts entering openings formed in the rocking frame when the latter is rocked forwardly to position the head over the buck; and a releasable lock for said thrust member.

3. In a garment press, the combination of a fixed buck; a tiltable platform; a head; a rockable support for the head resting on the

platform; means for locking the support to the platform with a degree of lost motion between the parts when the support is rocked to bring the head into juxtaposition with the buck; and means for drawing the support and head downwardly with the parts thus locked.

4. In a garment press, the combination of a main frame; a buck mounted thereon; a head; a head-carrying frame, said frame having a downwardly extending portion and an overhanging forwardly extending portion to which latter the head is secured, said frame being free to be moved manually in a forward direction to bring the head into alignment with the buck; means for guiding the head-carrying frame in its movements; spring means serving to elevate and move the head-carrying frame rearwardly; and operator operated means for effecting a pressing action between the head and buck.

5. In a garment press, the combination of a main frame; a buck mounted thereon; a head; a head-carrying frame, said frame having a downwardly extending portion and an overhanging forwardly extending portion to which latter the head is secured, said frame being free to be moved manually in a forward direction to bring the head into alignment with the buck; means for guiding the head-carrying frame in its movements; spring means acting in contraction to elevate and move the head-carrying frame rearwardly; and operator operated means for moving the head-carrying frame to produce a pressing action between the head and buck and simultaneously therewith to place the spring means under tension.

6. In a garment press, the combination of a main frame; a buck mounted thereon; a head; a head-carrying frame, said frame having a downwardly extending portion and an overhanging forwardly extending portion to which latter the head is secured, said frame being free to be moved manually in a forward direction to bring the head into alignment with the buck; means for guiding and supporting the head-carrying frame in its forward and rearward movements; spring means acting in contraction to elevate and move the head-carrying frame rearwardly; and operator operated means for effecting a pressing action between the head and buck.

7. In a garment press, the combination of a main frame; a buck thereon; a head; a head-carrying frame associated with the main frame; supporting means for the head frame; at least one spring acting in contraction to normally move the head-carrying frame to its elevated and rearward position with reference to the buck; operator operated thrust mechanism for effecting a downward movement of the head frame when the latter is in its extreme forward position, said thrust mechanism serving to carry the head into

pressing relation with the buck; and releasable means for locking the parts when thus positioned.

8. In a garment press, the combination of 5 a main frame; a buck thereon; a head; a head-carrying frame associated with the main frame; means for supporting said head frame in substantially counterbalanced condition whereby the head may be readily 10 moved toward and from pressing position with reference to the buck; means serving normally to elevate the head-carrying frame and to move it rearwardly with reference to the buck; and thrust mechanism serving to 15 swing the head carrying frame forwardly to bring the head into vertical alignment with the buck and thereafter to move the head vertically into pressing relation with the buck.

20 9. In a garment press, the combination of a main frame; a buck thereon; a head; a head-carrying frame associated with the main frame; means for supporting said head frame in substantially counterbalanced condition whereby the head may be readily 25 moved toward and from pressing position with reference to the buck; means serving normally to elevate the head-carrying frame and to move it rearwardly with reference to 30 the buck; and thrust mechanism acting to swing the head-carrying frame from its rear position to a position where the head is over the buck and to thereafter move the head frame downwardly and carry the head into 35 pressing relation with the buck.

10. In a press, the combination of a fixed frame; a buck thereon; a pressing head; a supporting frame for said head, said frame having a bodily movement vertically and laterally with reference to the fixed frame, 40 which latter movement carries the head toward and from the buck while in spaced relation thereto; spring means acting in tension to elevate the frame and to throw the head rearwardly clear of the buck; and means for moving the frame forwardly to align the head and buck and to draw the supporting frame and head downwardly and at the same time through such downward movement 45 place the spring means under tension.

11. In a garment press, the combination of 55 a fixed buck; a tiltable platform; a rockable support resting upon the platform; a head attached to the rockable support by means allowing a tilting of the head about its longitudinal axis; means for locking the support to the platform with a degree of lost motion between the parts when the support is rocked to bring the head into juxtaposition with the buck; and means for drawing the support and head downwardly with the parts thus locked.

12. A press as set forth in claim 11 where- 60 in the means for supporting the head is such

that it may tilt in all directions with reference to the buck.

13. In a garment press, the combination of a fixed buck; a tiltable platform; a rockable support resting upon the platform; a head 70 attached to the rockable support; a pair of bolts carried by the tiltable platform; means for projecting said bolts outwardly into elongated openings formed in the lower portion of the rockable support; and means for drawing the support and head downwardly with the parts thus locked.

14. A press as set forth in claim 13, wherein the bolts are located at the forward portion of the tiltable platform and the elongated openings are formed in the lower forward portion of the rockable support.

15. In a device of the class described, a buck; a head; arms supporting said head; rockers attached to and supporting said arms; 80 and means for shifting the rockers so as to throw the head to or away from the buck.

16. In a device of the class described, a buck; a head; arms supporting said head; rockers supporting said arms; means for 90 shifting the rockers so as to throw the head to or away from the buck; and means for locking the arms so as to hold the head adjacent to the buck.

17. In a press of the class described, the 95 combination of a buck; a head; arms supporting said head; rockers supporting said arms; a tiltable frame upon which said rockers rest; means for locking the rockers to the frame; and means for raising or lowering one end 100 of the frame so as to shift the rockers and thereby move the head toward and from the buck.

18. In a device of the class described, a buck; a head; arms supporting said head; 105 rockers supporting said arms; means for shifting the rockers so as to throw the head to or away from the buck and means for regulating the closeness of approach of the head to the buck.

19. In a press, the combination of a buck; a head; arms supporting said head; rockers supporting said arms; a pivoted frame upon which said rockers rest, said frame having downwardly curved ends at the forward portion thereof; a thrust frame; rollers carried by said thrust frame and engaging the curved portions of the first-named frame; means for locking the rockers to the frame; means for shifting said thrust frame inwardly and thereby causing the rollers to depress the rocker supporting frame; and springs normally holding the rocker supporting frame against the rollers.

20. In a garment press, the combination of 125 a base; a buck supported thereby; a frame pivotally mounted upon the base at the rearward portion thereof; springs serving to draw the forward portion of said frame upwardly; a thrust frame pivotally mounted 130

and arcuate members arranged to move said pressing elements toward and from each other when the latter are positioned one above the other.

- 5 30. In a garment press, the combination of two pressing elements, one movable relatively toward and from the other to effect the pressing operation; means for moving the movable element into pressing relation; and 10 rocking supporting means for said movable element, said means being so proportioned as to permit it to be rocked laterally away from the other, and returned to pressing position when said elements are separated, 15 all without substantial gravity resistance.
31. In a garment press, the combination of a fixed pressing element; a movable pressing element; a supporting member for the latter having arcuate members at its lower 20 portion; a pivoted member upon which the arcuate members rest and upon which they may be rocked; and means for locking said supporting member to the pivoted member and moving the same downwardly to produce 25 a pressing effect between the pressing elements.

32. In a garment press, the combination of a fixed frame; a pressing element supported thereby; a movable pressing element; 30 a supporting member therefor having arcuate members at its lower portion; a pivoted frame upon which the arcuate members rest and upon which they may be rocked to move the movable pressing element into and out of 35 position with reference to the fixed pressing element; a thrust element pivoted at its upper end; means for locking the supporting element to the pivoted frame when the former is rocked forwardly; means for moving the 40 thrust member inwardly with reference to the pivoted frame; and means cooperative with the thrust member to force the frame downwardly and to thereby lower the movable pressing element into contact with the other 45 pressing element.

33. In a garment press, the combination of a fixed frame; a buck supported thereon; a platform pivotally supported at the rear of the frame and extending forwardly thereof, 50 said platform having a pair of tracks and camming members extending forwardly of the tracks; a frame resting upon the tracks and having a rocking motion thereon; a pressing head carried by the upper portion 55 of the frame; a thrust member pivotally mounted at its upper end; rollers carried at the lower end of the thrust member and contacting the forward cam shaped portions of the pivoted platform; a treadle secured to the lower portion of the thrust member and extending outwardly therefrom; laterally arranged bolts carried by the pivoted supporting frame; and means attached to and movable with the thrust member for projecting such bolts outwardly into locking en-

gagement with the rocker supporting frame when the latter is drawn forwardly and the thrust member moved inwardly to effect a downward movement of the rocking frame and a consequent pressing action between 70 the head and buck.

34. In a garment press, the combination of a fixed buck; a pivoted member; a head; a rocking member upon which the head is supported, said rocking member resting upon 75 the pivoted member; a pivoted thrust member acting on the pivoted member to move the rocking member and the head downwardly in a right line toward the buck to effect a pressing action between the head and buck; 80 and means for actuating said thrust member.

35. In a garment press, the combination of a fixed buck; a pivoted member; a head; a rocking member upon which the head is supported, said rocking member resting upon 85 the pivoted member; a pivoted thrust member, adjustable as to effective length, acting on the pivoted member to move the rocking member and the head downwardly in a right line toward the buck to effect a pressing action between the head and buck; and means for actuating said thrust member.

36. In a garment press, the combination of a buck; a pivoted platform having cam surfaces at the free end thereof; a head; a support for said head including rocker members resting on the platform; means acting to draw the free end of the platform upwardly; a thrust member pivotally supported at its upper end, the lower end standing 100 over the cam surfaces on the free end of the platform; a pedal secured to the thrust member adjacent its lower end; means associated with the platform and support for locking said parts together when the support is rocked forwardly; and means movable with the pedal for actuating said locking means.

37. In a garment press, the combination with a buck; a platform; a head; a rocking support for the head mounted on the platform; means for limiting the rocking movement of the support in its forward and rearward direction; means to lock the support to the platform when the support is rocked forwardly; and means for lowering the platform and rocking support to bring the head 110 into pressing relation to the buck.

38. A garment or ironing press, comprising spaced upright members forming a frame; a press buck mounted on the frame; a press head to coat with the buck; an upright head carrying member at the rear of the frame, the lower end of which projects into the frame between the spaced members under the buck and the upper end of which 120 projects outside of the frame and extends forwardly above and is attached to the press head; pivotal means mounted on the frame below the buck for supporting the head carrying member whereby said head carrying 125

- in the upper portion of the press; a pedal carried on the lower portion of the thrust frame; rollers engaging the pivoted frame, said rollers being secured to the thrust frame;
- 5 a pair of rockers resting upon the pivoted frame; a head supported by said rockers; bolts carried by the pivoted frame; and means mounted upon the pedal for thrusting said bolts outwardly and locking the rockers
- 10 to the pivoted frame, after the head has been moved forwardly and over the buck.
21. In a garment press, the combination of a base; a buck supported thereby; a frame pivotally mounted at the rear portion of the base, the forward portion of the frame being provided with camming surfaces; a head; a rocker shaped support for said head, said support resting upon the pivoted frame; a thrust member pivotally supported at its upper end; a pedal attached to the lower end of the thrust member; rollers mounted upon the pedal in line with the cam faces aforesaid; and locking means actuated upon an inward movement of the pedal to lock the rockers to the pivoted frame so that when the pedal is moved inwardly to its fullest extent the rollers will depress the pivoted frame and as a consequence draw the rockers and the head carried thereby downwardly, and the head carried thereby downwardly, bringing the head and buck into operative relation.
22. In a garment press, the combination of a base; a buck supported thereon; a frame pivoted at its rear end to the rear portion of the base; a head; rocking supports for said head resting upon the pivoted frame; means for normally drawing the forward portion of the frame upwardly; a thrust member pivotally supported at its upper end; a pedal attached to said thrust member; means interposed between the thrust member and the pivoted frame for forcing the frame downwardly as the pedal is moved inwardly; a pair of bolts secured to the pivoted frame; means for drawing said bolts inwardly; and a cam cooperating with the bolts and carried by the pedal for forcing the bolts outwardly into locking relation with the rockers upon the initial inward movement of the pedal.
23. In a press, the combination of a fixed main frame; a buck thereon; a pressing head; a supporting frame therefor, said frame having a forwardly extending portion to which the head is attached and likewise having a rear, downwardly extending portion; means cooperating with said last named portion for supporting and guiding said supporting frame to carry the pressing head toward and from the buck; and means for drawing the supporting frame downwardly to effect a pressing action between the head and buck.
24. In a press, the combination of a fixed main frame; a buck thereon; a pressing head; a supporting frame therefor, said frame having a forwardly extending portion to which the head is attached and likewise having a rear, downwardly extending portion; means cooperating with said last named portion for supporting and guiding said supporting frame to carry the pressing head toward and from the buck; and means for drawing the supporting frame downwardly to effect a pressing action between the head and buck.
25. In a garment press, the combination of a fixed frame; a buck mounted thereon; a platform pivotally supported at the rear of the fixed frame; a rocking frame supported on the platform; a pressing head carried by the upper portion of the rocking frame; means for locking said frame to the platform when the frame is rocked forwardly; and means for forcing the platform downwardly when the parts are so locked whereby the head will be forced against the buck.
26. In a garment press, the combination of two pressing elements; a rocking support for one of the elements permitting the same to be moved over and into spaced relation with the other; and means for thereafter forcing the pressing elements into contact through substantially right-line movement when thus positioned.
27. In a garment press, the combination of a fixed buck; a head; a rocker-like support for said head whereby the head may be moved laterally over, in spaced relation to the buck, and also to the rear of the buck; and means for lowering the support when the head is over the buck to effect a direct pressing action between the head and buck.
28. A garment press comprising in combination two pressing elements, one movable relatively toward and from the other to effect the pressing operation; supporting means for the upper of said pressing elements including a track and an arcuate member engaging said track and secured to said upper element, the parts being so proportioned that the upper pressing element and the arcuate element roll on said track without substantial vertical movement of their combined center of gravity to effect a lateral displacement of the upper pressing element relatively to the lower pressing element; and means for drawing said upper element downwardly into pressing relation with reference to the other pressing element.
29. In a garment press, the combination of two pressing elements; supporting means for the upper of said elements including a track and arcuate members rolling on said track, said members being connected with said upper pressing element, the parts being so proportioned that the head and arcuate member roll on the track without substantial vertical displacement of their combined center of gravity to shift said upper pressing element laterally relatively to said lower pressing element; and means acting through said track

member may be swung through a compound movement; means carried on the frame and cooperating with the pivotal means for rocking said pivotal means and thereby moving the head to closed position; means urging the head carrying member upwardly to open the press; and foot operating means associated with the frame carried means to draw downwardly upon the head carrying member.

10 In testimony whereof I have signed my name to this specification.

WILLIAM A. ZEIDLER.

CERTIFICATE OF CORRECTION.

Patent No. 1,872,100.

August 16, 1932.

WILLIAM A. ZEIDLER.

It is hereby certified that the above numbered patent was erroneously issued to "The Zeidler Corporation, of New York, N. Y., a corporation of New York," as assignee of the entire interest in said invention, whereas said patent should have been issued to United States Hoffman Machinery Corporation, of New York, N. Y., a corporation of Delaware, as assignee by mesne assignments of the entire interest in said invention as shown by the records of assignments in this office; page 5, lines 37 and 53, claims 1 and 2, respectively, for "trust" read thrust; and that the said Letters Patent should be read with these corrections therein that the same may conform to the record of the case in the Patent Office.

Signed and sealed this 22nd day of November, A. D. 1932.

M. J. Moore,
Acting Commissioner of Patents.
